United States Patent Office

Des. 203,159
Patented Dec. 14, 1965

203,159

RAILING POST

Louis Blum, Pittsburgh, Pa., assignor to Blumcraft of Pittsburgh, Pittsburgh, Pa.

Filed Mar. 5, 1959, Ser. No. 54,864

Term of patent 14 years

The portion of the term of the patent subsequent to Apr. 23, 1977, has been disclaimed

(Cl. D13—7)

The figure is a perspective view of a railing post embodying my new design.

The dominant features of my design are shown in solid lines.

I claim:

The ornamental design for a railing post, as shown and described.
